UNITED STATES PATENT OFFICE.

ALBERT F. KRAUSE, OF BUFFALO, NEW YORK, ASSIGNOR TO HYDRO VACUUM CLEANER COMPANY, OF BUFFALO, NEW YORK, A CORPORATION OF NEW YORK.

SAFETY-CATCH FOR VACUUM-CLEANERS.

1,200,855.

Specification of Letters Patent.

Patented Oct. 10, 1916.

Application filed December 2, 1911. Serial No. 663,501.

To all whom it may concern:

Be it known that I, ALBERT F. KRAUSE, a citizen of the United States, residing at Buffalo, in the county of Erie and State of New York, have invented new and useful Improvements in Safety-Catches for Vacuum-Cleaners, of which the following is a specification.

This invention relates generally to vacuum cleaners and more particularly to the means employed for intercepting any lint, paper, matches, &c., drawn into the suction nozzle, in order to avoid clogging of the apparatus or impairment of its action.

The invention has special reference to vacuum cleaners controlled by water power and in which the dust in the air is drained into a sewer or other place of discharge by the spent water, but the invention is not confined to this particular use.

One object of my invention is to combine means with the screen for keeping lint, matches and other foreign substances, other than dust, in suspension above the screen during the operation of the apparatus to avoid clogging of the screen and allow the dust to pass through it with the air and to be drained into the sewer.

Another object of my invention is the production of an efficient and inexpensive device of this character which can be readily emptied from time to time and which shall not affect the suction-power of the cleaner.

In the accompanying drawings consisting of 2 sheets: Figure 1 is a sectional perspective view of a building equipped with a permanently-installed cleaner embodying the invention. Fig. 2 is a vertical section of the intercepting device, the plane of the section being on the line 2—2, Fig. 3. Fig. 3 is a sectional top plan view of the device. Fig. 4 is a side elevation of a slightly modified construction of the device. Fig. 5 is a sectional top plan view of said modification. Fig. 6 is a sectional elevation of the cover and the screen connected therewith.

Similar characters of reference indicate corresponding parts throughout the several views.

1 indicates a vacuum producing apparatus of any suitable construction. The apparatus illustrated in the drawings is located in the cellar or basement of the building and comprises a pair of exhaust pumps 2 oper-

ated by a water motor, not shown, from which leads the discharge pipe 3 for the mixture of water and dust which is usually drained into the sewer.

4 indicates the main or stationary suction pipe connected with the apparatus 1 by a flexible tube 5 and usually extending to the upper floor of the building.

6 indicates one of the suction nozzles and its tube or hose adapted to be detachably connected with one of the improved interceptors or intercepting devices 8 which in turn are connected with or interposed in the main suction pipe 4. In practice one of these interceptors may be located on each floor and that of the uppermost story is preferably attached to the upper end of the suction pipe 4 and located under an opening in the floor normally closed by a door 9; while each of the interceptors on the remaining floors is located in a partition having a door 10 in its base board which normally conceals the interceptor. A similar interceptor 11 may also be interposed in the connection between the pumps 2 and the main suction pipe 4. As best shown in Fig. 2, each of these interceptors comprises an imperforate casing, receptacle or chamber 12 preferably of cylindrical form provided at its lower end with an outlet or screw stem 13 by which it is connected with the main suction pipe 4, either directly as shown in Fig. 1, in connection with the interceptor of the uppermost story; or by a horizontal branch pipe 14, as shown in connection with the interceptor of the lower story. Removably arranged within this casing is a screen or "safety catch" 15 having perforations of the proper size to permit the free passage of the air and dust therethrough, but so small as to intercept lint, pieces of paper, matches and other foreign substances commonly drawn into the suction nozzle of a vacuum cleaner. This screen is preferably cup-shaped, as shown, and provided at its upper end with an outwardly-extending flange 16 by which it is removably suspended from an internal shoulder 17 of the casing. The screen is perforated in its sides as well as its bottom and is separated from the wall of the casing 12, as shown in Fig. 2, to permit the free passage of the dust-laden air through all portions of the screen.

100
105

Applied to the top of the casing is a removable cover 18 which is seated in a rabbet 19 in the upper end of the casing, a packing gasket 20 being preferably interposed between the cover and the flange of the screen to form an air-tight joint. The cover may be secured in place by a clamping yoke 21 or other suitable means.

In the construction shown, the ends of the 10 yoke are turned inwardly under a flange 22 projecting outwardly from the upper end of the casing, and the yoke carries a clamping screw 23 which bears upon a central boss of the cover 18. The latter is thus securely clamped upon the casing and in turn 15 clamps the flanged screen in place in the casing.

As shown in Figs. 2 and 3, the casing 12 is provided above the screen 15 with an inlet 20 or inlet tube 24 to which the hose 7 of the suction nozzle 6 is suitably attached. This inlet is preferably located in or carried by the cover 18 and is arranged tangentially to the casing, as shown, so that the air, dust, 25 &c., drawn into the casing 12 are caused to whirl or gyrate therein during the operation of the vacuum cleaner. The air and dust pass onward through the screen, the outlet 13 and the pumps to the sewer or other 30 place of discharge, while the intercepted lint, paper, &c., continue to whirl and remain in suspension in the screen during the operation of the cleaner. The result is that 35 these foreign substances are prevented from settling into and clogging the screen, intercepting the dust and obstructing the passage of the air through the screen. This whirling action of the air current has a tendency to drive the foreign matters other 40 than the dust, such as lint, paper, &c., toward the center of the screen, while the dust moves onward through the screen with the air, thus effecting a separation within the screen of such foreign matters from the 45 dust. Moreover, this whirling action of the dust-laden air current maintains the necessary velocity thereof to compensate for the loss of velocity due to the enlargement of the portion of the suction conduit formed by 50 the chamber of the safety catch, thus maintaining the portative power of the air current.

When the vacuum cleaner is stopped, the 55 intercepted accumulations settle into the screen 15 which is emptied from time to time after removing the cover 18. As these accumulations are practically freed from dust by the above described action they are not liable to contain germs, rendering the 60 duty of emptying the screen less objectionable from a sanitary view point than would be the case if no such separation were effected.

As shown in Figs. 2 and 3, the interceptor 65 located on the top floor preferably has its

tangential inlet provided with a vertical or upwardly-extending branch 25 to more conveniently receive the hose of the nozzle upon opening the door 9; while the tangential inlet of each of the intercepting devices on the lower floors may be horizontal throughout its length, as shown in Figs. 4 and 5.

When the suction nozzles 6 are not in use 70 they are detached from the casings 8 and the inlets 24 are closed by a suitable valve 75 or plug 26.

The screen is preferably connected with the cover 18 in such manner that it is removable therewith and when removed is suspended at a suitable distance below the 80 cover to permit the emptying of the screen by using the cover as a handle therefor, thus avoiding the necessity of touching the screen itself and rendering the device more sanitary. For this purpose, a depending suspension rod 27 is secured centrally to the 85 cover. This rod passes loosely through an opening in the bottom of the screen and is provided at its lower end with a stop or nut 28 which retains the screen upon the rod. 90 The rod extends some distance below the bottom of the screen in the operative position of the latter, so that upon removing the cover, it is separated a corresponding distance from the top of the screen before being 95 lifted out of the casing, as shown in Fig. 6, thus leaving the necessary space between the cover and the removed screen for emptying the contents of the latter, which is done by 100 grasping the cover and tilting it sufficiently 105 for this purpose. By fitting the rod rather loosely in the bottom opening of the screen, the latter tilts on the rod and assumes an inclined position, as shown in Fig. 6, facilitating the discharge of its contents.

My improved intercepting device or safety 110 catch not only furnishes a convenient means of connecting the suction-nozzle conduits to the main suction-pipe 4, but effectively guards against clogging of the suction 115 pumps, their valves and the pipe-system, without impairing the cleaning action of the apparatus.

As before stated, an interceptor similar to the devices shown in Figs. 2 and 5, may be 115 advantageously placed at the junction of the pump inlets and the main suction pipe, as shown in Fig. 1.

I claim as my invention:

1. An intercepting device for a vacuum 120 cleaner, comprising a chamber closed at its top and having an inlet and an outlet, a screen arranged in said chamber between its inlet and outlet and having perforations of the proper size to permit the passage of the 125 dust-laden air therethrough while intercepting lint, paper and other foreign substances, and means for producing a whirling motion of the air current in said chamber on the inlet side of said screen to keep such sub- 130

stances other than dust in suspension in said chamber and prevent their clogging the screen during the operation of the cleaner.

2. An intercepting device for a vacuum 5 cleaning apparatus, comprising a chamber closed at its top and having an outlet and a tangential inlet to produce a whirling motion of the incoming air and hold lint and similar substances in suspension in said 10 chamber, and a screen arranged in said chamber between its inlet and outlet and having perforations large enough to permit the passage of dust but so small as to intercept lint, paper and other foreign substances. 15

3. An intercepting device for a vacuum cleaning apparatus, comprising an upright chamber closed at its top by a removable cover and having an outlet at its lower end, 20 said cover having a tangential inlet for the dust-laden air, and a cup-shaped screen removably arranged in said chamber between said inlet and said outlet and having perforations large enough to permit the passage of dust but so small as to intercept lint, paper and other foreign substances. 25

4. An intercepting device for a vacuum cleaning apparatus, comprising a chamber

having an inlet, an outlet and a removable cover, a screen removably arranged in said 30 chamber between its inlet and outlet and held in place by said cover, and a loose connection between the screen and the cover for withdrawing the screen from said chamber by means of the cover, said connection being 35 constructed to permit limited movement of the cover relative to the screen to leave an emptying-space between the cover and the screen.

5. An intercepting device for a vacuum 40 cleaning apparatus, comprising a chamber having an inlet, an outlet and a removable cover, a screen removably arranged in said chamber between its inlet and outlet, a suspension rod depending from the cover and 45 passing loosely through the screen, said rod extending normally below the screen and having at its lower end a stop which supports the screen when removed from said chamber. 50

Witness my hand this 28th day of November, 1911.

ALBERT F. KRAUSE.

Copies of this patent may be obtained for five cents each, by addressing the "Commissioner of Patents, Washington, D. C."

It is hereby certified that in Letters Patent No. 1,200,855, granted October 10, 1916, upon the application of Albert F. Krause, of Buffalo, New York, for an improvement in "Safety-Catches for Vacuum-Cleaners," an error appears in the printed specification requiring correction as follows: Page 3, line 46, claim 5, after the word "screen" insert the words *to slide therein when the cover is removed*; and that the said Letters Patent should be read with this correction therein that the same may conform to the record of the case in the Patent Office.

Signed and sealed this 31st day of October, A. D., 1916.
